UNITED STATES PATENT OFFICE.

LESTER WILLIAM BORCHERT, OF CLEVELAND, OHIO.

FLASH-LIGHT.

1,280,380.

Specification of Letters Patent.

Patented Oct. 4, 1918.

Application filed January 26, 1918. Serial No. 314,008.

To all whom it may concern:

Be it known that I, LESTER WILLIAM BORCHERT, a citizen of the United States, residing at Cleveland, in the county of 5 Cuyahoga and State of Ohio, have invented new and useful Improvements in Flash-Lights, of which the following is a specification.

This invention relates to new and useful 10 improvements in lighting means and the principal object of the invention is to provide a float or boat like member containing electric lamps and batteries and provided with a transparent top portion through 15 which the light may pass in all directions.

The invention is particularly adapted for use at sea when launching the life-boats 20 from a vessel and is used to illuminate the vicinity of the vessel so that the various operations of launching the boats may be readily carried out and at the same time to provide a signal to other vessels and to direct them to the sinking ship.

The invention will be useful in cases 25 where the electrical plant of a vessel has been put out of service and the lighting system and wireless cannot be used.

The invention also consists in certain other features of construction and in the 30 combination and arrangement of the several parts, to be hereinafter fully described, illustrated in the accompanying drawings and specifically pointed out in the appended claim.

35 In describing my invention in detail, reference will be had to the accompanying drawings wherein like characters denote like or corresponding parts throughout the several views, and in which:—

40 Figure 1 is a view showing the invention in use on a vessel.

Fig. 2 is a top view of the float.

Fig. 3 is a longitudinal sectional view.

Fig. 4 is a cross section.

45 As shown in the drawings the device forming the subject matter of this invention comprises a body part 1 made in the shape of a small boat having its top closed and provided with the step-like arrangement of 50 parts shown in the figures, the central part

being the highest. These step-like parts are provided with transparent portions so as to direct the light contained within the device in all directions. In the center of the device above the middle part is a searchlight apparatus 2 which consists of a cylindrical lens below which is placed the usual reflectors and a powerful electric light 3. Electric lights 4 are located at intervals below the transparent parts in the top and these lights are connected with the batteries 5 located within a casing 6, preferably made of aluminum, within the body of the boat. At each end of the device is located a fastening member 7 to which cables are secured to secure the device to the ordinary launching members 8 on the vessel. As shown in Fig. 1 the lighting device is preferably located below the life-boat on the launching members and I prefer to extend the cable from said lighting device to the life-boat so that the current may be turned on from the life-boat. Thus when it is necessary to launch the life-boats the light is first turned on so that the life-boat will be illuminated and the passengers and crew may readily take their places therein. As the life-boat is swung outwardly the lighting member is carried with it and when the life-boat strikes the water the lighting device will be adjacent the same to one side thereof so that it will still illuminate the life-boat and the water about the same. The lighting device is released from the launching means by the crew and may be towed by the life-boat so as to furnish light therefor. The search light arranged in the middle of the device will cast its beam straight up thus notifying other vessels that help is needed and also acting to direct said vessels to the scene of disaster. As the lamps give off a certain amount of heat the same may be utilized to warm the occupants of the life boat when necessary. The top may be provided with hinged portions to permit access to the interior of the member.

It is thought from the foregoing description that the advantages and novel features of my invention will be readily apparent.

I desire it to be understood that I may make slight changes in the construction and

in the combination and arrangement of the several parts, provided that such changes fall within the scope of the appended claim.

What I claim is:—

6 A device of the class described comprising a floating member in the form of a small boat, electric lamps in the top thereof, batteries carried by said member and connected with 4 lamps, a top for said member hav-

ing a central raised portion, and intermediate portions surrounding the same and arranged in step-like formation, transparent means in said portions, a search light located in the middle of the raised portion and cable receiving means at each end of the 15 member.

In testimony whereof I, affix my signature.
LESTER WILLIAM BORCHERT.
